UNITED STATES PATENT OFFICE.

ARTHUR E. SHAW AND EDWARD S. SANDERSON, OF PHILADELPHIA,
PENNSYLVANIA, ASSIGNOR TO THE PENNSYLVANIA GLOBE GAS
LIGHT COMPANY, OF PENNSYLVANIA.

DESIGN FOR A STREET-LAMP.

SPECIFICATION forming part of Design No. 81,745, dated October 31, 1899.

Application filed September 23, 1899. Serial No. 731,496. Term of patent 14 years.

To all whom it may concern:

Be it known that we, ARTHUR E. SHAW and EDWARD S. SANDERSON, citizens of the United States, residing at Broad and Arch streets, 5 Philadelphia, in the county of Philadelphia and State of Pennsylvania, have invented and produced a new and original Design for a Street-Lamp, of which the following is a specification, reference being had to the accompanying drawing, forming part thereof.

As shown in the drawing, the leading feature of the design comprises a harp *a*, which comprises a base and two arms having surface ornamentation and being surmounted by 5 a crown-like ring *b*, ornamented with leaf-like formss from which depends an inverted-

bell-shaped structure *e*, of which the skirt encircles the base of the harp. From the crown-like ring *b* rises a dome *c*, which is surmounted by an ornamental cap *d*.
